United States Patent

Des. 237,545
Patented Nov. 4, 1975

237,545

PHOTOGRAPHIC ENLARGER OR SIMILAR ARTICLE

Haruki Yamaguchi, Toyokawa, and Masakazu Nakanishi,
Hashimoto, Japan, assignors to Minolta Camera Ka-
bushiki Kaisha, Osaka, Japan

Filed Jan. 17, 1974, Ser. No. 434,310

Claims priority, application Japan July 18, 1973

Term of patent 14 years

Int. Cl. D16—03

U.S. Cl. D61—1 Q

FIG. 1 is a front elevational view of a photographic enlarger or similar article embodying our new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof.

We claim:

The design for a photographic enlarger or similar article, as shown and described.
